DRAFT GEAR

Herbert E. Van Dorn, Chicago, Ill., assignor to
The Dornvan Corporation, a corporation of
Illinois

Application July 19, 1939, Serial No. 285,257

11 Claims.

(Cl. 213—64)

In the ordinary draft gear construction for railway cars, the portion in the region of the spring cushioning means is roughly constructed, in the sense that there is substantially no machining of parts except the drilling of holes where these are necessary to receive fastenings. As a result, there is considerable looseness in the draft gear as a whole, which produces noise and unnecessarily rapid wear, and which prevents accuracy of adjustment. Although the development of railway equipment has been in the direction to provide smooth, noiseless operation, the useless lost motion in the draft rigging has not heretofore been eliminated even though the coupler heads are no longer required to move lengthwise more than an inch or so. The reason for this failure to employ precision work in connection with the construction that provides the cushioning means, is that the necessary machining to take up all unnecessary slack, in draft gears as heretofore constructed, could only have been done at a prohibitive cost.

The object of the present invention is to provide a draft gear in which the coupler shank and the drawbar proper are connected together in such a manner that there is no unnecessary looseness or lost motion, without any considerable increase in the cost over the cost of the old types.

In carrying out my invention, I provide the coupler shank with a housing which, when the draft gear is in use, is closed against the entrance of dirt, which provides machined bearing surfaces for the front end of the drawbar to permit the necessary relative movements and prevent those that are unnecessary or undesirable, and which permits the bearing surfaces to be adequately lubricated. The parts are so constructed that the machine work is quite simple and easily done.

The various features of novelty whereby my invention is characterized will hereinafter be pointed out with particularity in the claims; but, for a full understanding of my invention and of its objects and advantages, reference may be had to the following detailed description taken in connection with the accompanying drawings, wherein:

Figure 1 is a top plan view of a draft gear, including the means for anchoring the same to the car, embodying the present invention, the coupler head being shown in broken lines and a portion of the coupler being omitted; Fig. 2 is a side view of the assembly shown in Fig. 1, a portion of the anchor being broken away to ex-

pose the ball and socket joint; Fig. 3 is a view partly in top plan and partly in longitudinal section of the spring housing and the front end of the drawbar; Fig. 4 is a central longitudinal section through the parts shown in Fig. 3; Fig. 5 is a section on line 5—5 of Fig. 3; Fig. 6 is a section taken on line 6—6 of Fig. 4; and Fig. 7 is a section taken on line 7—7 of Fig. 4.

Referring to the drawings, 1 represents the shank of a so-called tight-lock coupler. This shank is enlarged at its rear end into the form of a housing 2 which is open at its rear end. The coupler shank, as is customary, is hollow and, therefore, to close the front end of the housing, I form a transverse wall or partition 3 at the point where the housing merges into the shank. The general shape of the housing in transverse section is rectangular. The central longitudinal panels of the top and bottom walls are bulged upwardly and downwardly, respectively, as indicated at 4, constituting sections of a cylindrical shell having its axis coinciding with the longitudinal axis of the shank; the diameter of the cylinder being, of course, less than the width of the housing. The flat portions of the top and bottom walls, and the side walls of the housing are provided with shallow bosses 5 of considerable diameter distributed along the same. Holes 6, of substantial size, are drilled through the housing walls at the centers of these bosses; these holes being large enough to permit the insertion of a tool for facing the bosses.

In order to take the wear incident to the movement of the parts of a spring cushioning unit, I provide what may be termed the wing sections of the housing, namely, the sections provided with the bosses just described, with wearing plates or linings which are in the form of channel-shaped members 7 of hard steel, such as manganese steel; these wearing plates being of such size and shape that all three walls of each bear against the bosses in the corresponding section of the housing; the wearing plates being somewhat shorter than the housing to provide room for stationary stops beyond the ends thereof. The flanges of each wearing plate are preferably securely fastened to the upper and lower walls of the housing, although they need not be fastened to the vertical side walls. Since the holes 6 through the bosses are larger in diameter than necessary to receive suitable bolts, the holes in the upper and lower bosses are provided with fairly thick bushings 8. Short bolts extend through the flanges on the wearing plates and through these

bushings; the heads of the bolts being on the inside and being counter-sunk in the wearing plates, and the nuts 10 being on the exterior of the housing.

The rounded portions of the top and bottom walls of the housing can be quickly and easily machined by means of a suitable boring tool inserted through the rear end of the housing and moved throughout the length thereof. In order to insure accuracy in the machining, I prefer to provide the partition 3 at the front end of the housing with a central opening 4 of considerable diameter; this opening being reamed so as to form an effective bearing for the front end of a boring tool. After the machining has been completed, this opening may be closed by inserting a suitable plug 12 in the same. The machining of the interior of the housing extends to the open rear end so that the cylindrical interior surface and the edge face at the rear end may be completed in one operation. The cylindrical inner surface of the housing need not be continuous from end to end, but it may be in the form of distributed bands, as shown, one such band being at the open end.

Any suitable type of cushion may be employed, as long as its transverse and vertical dimensions are such as to permit it to be engaged at its side marginal portions in the troughs of the wearing plates. Some means must be provided, however, to serve as front and rear stops. In order accurately to locate these stops, so that throughout an indefinite number of draft gears the distance of the stops from the coupler faces will be exactly the same, I do not cast them integral with the housing, but construct them separately and secure them in the housing.

In the arrangement shown, each of these stops is in the form of a tall square block 14 which rests upon a boss 15, similar to one of the bosses 5, on the bottom wall of the housing, either just in front of or just behind one of the wearing plates. Heavy pins 16 extend through the housing from top to bottom, each pin passing through one of the blocks 14. It will be seen that the holes through which the pins extend permit the insertion of a tool for facing the bosses 15, so that a true bearing face may be provided on each of these bosses, just as in the case of the bosses 5. Since the two forward blocks need not be removed after once having been placed in position, the holding pins therefor may be a pressed fit in the housing walls and blocks. However, the two rear pins must be removable so as to permit the two rear stop blocks to be taken out when desired. The forward stops are the ones apt to be subjected to the severest shocks, since the buffing stresses caused by blows on the coupler heads tending to drive them rearwardly, and which are more severe than the pulling stresses, must be absorbed by these stops. In order to shield the forward pins 16 against abnormal shearing stresses, I provide each side wall of the housing, where it slopes inwardly and forwardly to meet the coupler shank, as indicated at 17, with a longitudinal rib 18 lying about halfway between the top and bottom of the housing. Each of these ribs has a thickened edge portion 19 which bears against the front face of the corresponding block 14. Therefore, there is a direct thrust from the housing against each of the forward stops which transmits a portion of the shock independently of the holding pins.

In the arrangement shown, the cushion unit is a well known type of spring cushion comprising

plural groups of spring plates 20 alternating with rigid followers 21 and spacing plates 22 and 24. The elements constituting this unit are assembled and held under initial compression in a drawbar yoke 25. This drawbar yoke is preferably formed integral with a hollow cylindrical drawbar 26; the opening or window in the yoke, while being shorter than the spring cushion in its expanded condition, is of greater height than the elements of the cushion, so that the longitudinal members of the yoke do not touch the parts of the spring cushion. This yoke is machined on the exterior so that when it is set on edge, with one of its longitudinal members on top and one on the bottom, it fits the internal cylindrical faces of the housing. The angular width of the curved faces of the yoke is less than that of the seats therefor in the housing, so that the housing may rock through a small angle about the longitudinal axis of the assembly. In order to provide a maximum rocking movement without having the longitudinal members of the yokes spread apart too far, I prefer to cut away the inner face of each of these members on a rising incline from the outer edges 25 toward the center, as indicated at 27; or, in other words, the inner face of each of the longitudinal members of the yoke is made convex.

The bearing surfaces between the yoke and the housing may be lubricated in any suitable way. 30 In the arrangement shown, the housing has a number of grease openings in the top and bottom; these openings being provided with suitable grease-receiving nipples 28. Grease from each nipple flows through registering grooves or channels 29 in the periphery of the yoke and the bearing surfaces for the yoke.

The rear end of the housing is closed by a suitable head or end constructed in two sections 30 and 31 meeting along a horizontal plane containing the axis of the coupler. The two-part head is provided with an inward projection 32 that fits into the end of the housing, whereby the housing keeps the two sections of the head from spreading apart in a direction transverse to the longitudinal axis. The head is fastened to the housing by means of four machine screws 34 which extend through the head at what may be termed the four corners thereof and into the external thickened portions or bosses 35 which stiffen the top and bottom walls of the housing in the regions where the rear pins 16 extend through the same. The divided head has a central circular opening 36 slightly larger in diameter than the body of the drawbar 26. In the edge 45 bounding this opening is an annular groove 37 containing a sealing ring 38 of felt or other suitable packing material which engages with the periphery of the drawbar when the structure as a whole is assembled, and prevents dirt and other foreign matter from entering the housing through the opening that receives the drawbar.

The drawbar terminates at its rear end in a ball 39 of large diameter which is seated in a socket in a suitable rigid anchor fixed to the under side of the car frame. In the arrangement shown, the anchor comprises an upper member 40 which rests against and is secured to the car structure, and a lower member 41; the two members meeting in a horizontal plane and being secured together by a number of sturdy vertical bolts 42. Furthermore, in one of the meeting faces between said members there may be an annular groove, while the other may be provided with an annular rib that fits into the groove and thus relieves the bolts of some of

the shearing stresses which would otherwise be imposed upon the same. There may be placed a bellows-like flexible shield 43 in position to cover the entrance of the drawbar into the anchor casting. In the arrangement shown, this device surrounds the drawbar and is clamped at its forward end tightly against the drawbar, while its rear end lies against a flat front face of the anchor casting and is secured thereto in a manner to produce a tight joint.

It will thus be seen that I have produced a simple, rugged draft gear which permits the coupler to move longitudinally and angularly relatively to the drawbar, in a smooth and soundless manner, and in which, by reason of the sealed housing and the facilities for lubricating the engaging, relatively movable surfaces, the conditions initially established may be indefinitely maintained. Furthermore, because the stops in front of and behind the spring cushion are applied after the housing has been cast, they may be accurately located through measurements for the centers of the bolt holes, made from the face of the coupler head as a base line. It will also be seen that the machining of the housing to permit the attaining of the desired results is very simple and thus does not add greatly to the cost of the apparatus.

While I have illustrated and described with particularity only a single preferred form of my invention, I do not desire to be limited to the exact structural details thus illustrated and described; but intend to cover all forms and arrangements which come within the definitions of my invention constituting the appended claims.

I claim:

1. In combination, a car coupler having at the rear end a rearwardly-opening housing, a drawbar having a yoke including parallel longitudinal members extending into the housing from the rear, the housing and said longitudinal members of the yoke having complementary bearing faces in the form of surfaces of revolution about the longitudinal axis of the housing, a spring cushion unit embraced by the yoke but standing clear from the longitudinal members of the latter, stops in the housing at the ends of the spring units, and a closure for the rear end of the housing extending around the drawbar.

2. In combination, a coupler having at the rear end a rearwardly-opening housing, a drawbar having a cylindrical stem extending a short distance into the rear end of the housing and a yoke including parallel longitudinal members at the front end of the stem, a closure for the open end of the housing surrounding the drawbar stem, the housing and said longitudinal members of the yoke having complementary bearing faces to permit relative longitudinal movements and relative rotary movements of limited extent about the longitudinal axis of the housing while preventing other relative movements, a cushion unit within the housing embraced by said yoke, and stops in the housing at the ends of said cushion unit.

3. In combination, a coupler having at the rear end a rearwardly-opening housing, a drawbar having a cylindrical stem extending a short distance into the rear end of the housing, a yoke at the front end of the stem including longitudinal members spaced apart from each other, a closure for the open end of the housing surrounding the drawbar stem, the longitudinal members of the housing and the yoke having complementary bearing faces to permit relative longitudinal

movements and relative rotary movements of limited extent about the longitudinal axis of the housing while preventing other relative movements, a cushion unit within the housing embraced by said yoke, stops in the housing at the ends of said cushion unit, means to support the cushion unit to restrict the parts thereof to movements longitudinally of the housing, and the longitudinal members of the yoke standing clear of the cushion unit.

4. In combination, a coupler having at its rear end a rearwardly-opening housing, said housing having at the top and bottom internal faces forming parts of the surface of a cylinder coaxial with the housing, the interior of the housing being widened at the sides, longitudinal wearing plates U-shaped in cross section fixed in opposite sides of the housing in the widened portion of the latter, a drawbar extending into the open rear end of the housing and having bearing faces complementary to and engaged with the cylindrical faces in the housing, and a cushion unit associated with the drawbar and extending between and engaged with said wearing plates.

5. In combination, a coupler having at its rear end a rearwardly-opening housing, said housing having at the top and bottom internal faces forming parts of the surface of a cylinder coaxial with the housing, the interior of the housing being widened at the sides, longitudinal wearing plates U-shaped in cross section fixed in opposite sides of the housing in the widened portion of the latter, a vertical block positioned within the housing in front of and behind each wearing plate, a sturdy pin extending vertically through each block and through the top and bottom of the housing, a cushion unit supported by said wearing plates and engaged at its ends with said blocks, and a drawbar device extending into the housing from the rear and operatively connected to said cushion unit.

6. A car coupler having at its rear end a rearwardly-opening housing, said housing having in cross-section the shape of a rectangle the central portions of the top and bottom sides are in the form of arcs of a circle having its center at the center of the rectangle, the side walls and the top and bottom walls of the housing having large shallow bosses projecting inwardly thereupon, and a U-shaped wearing plate arranged in each side of the housing and fitting against the bosses above, below and beside the same.

7. A car coupler having at its rear end a rearwardly opening housing, said housing having in cross-section the shape of a rectangle the central portions of the top and bottom sides are in the form of arcs of a circle having its center at the center of the rectangle, the side walls and the top and bottom walls of the housing having large shallow bosses projecting inwardly therefrom, a U-shaped wearing plate arranged in each side of the housing and fitting against the bosses above, below and beside the same, and fastenings extending through each of the upper and lower flanges of each wearing plate and the bosses engaged by that flange.

8. A car coupler having at its rear end a rearwardly-opening housing, said housing having in cross-section the shape of a rectangle the central portions of the top and bottom sides are in the form of arcs of a circle having its center at the center of the rectangle, the side walls and the top and bottom walls of the housing having large shallow bosses projecting inwardly therefrom, the walls of the housing having large holes extending

through the same at the bosses, and bushings in the holes in the top and bottom walls.

9. A car coupler having at its rear end a rearwardly-opening housing, said housing having in cross-section the shape of a rectangle the central portions of the top and bottom sides are in the form of arcs of a circle having its center at the center of the rectangle, the side walls and the top and bottom walls of the housing having large shallow bosses projecting inwardly therefrom, a U-shaped wearing plate arranged in each side of the housing and fitting against the bosses above, below and beside the same, the bosses on the upper and lower walls having openings therein large enough to receive a tool to face the bosses, bushings in said holes, and bolts extending through said bushings and the corresponding flanges of the wearing plate to secure the wearing plates to the housing.

10. In combination, a car coupler having at the rear end a rearwardly-opening housing, a cylindrical drawbar extending into the housing, a yoke including parallel longitudinal members fixed to the front end of the drawbar, the housing and the longitudinal members of the yoke having complementary bearing faces in the form of surfaces of revolution about the longitudinal axis of

the housing, means to lubricate said faces, a spring cushion unit embraced by the yoke but standing clear from the longitudinal members of the latter, stops in the housing at the ends of the spring unit, a closure for the rear end of the housing extending around the drawbar, and means to seal the joint between the drawbar and the closure.

11. In combination, a coupler having at the rear end a closed housing provided with an opening in its rear end, a drawbar having a cylindrical stem extending through said opening into the housing and a yoke at the front end of the stem, said yoke including parallel longitudinal members, sealing means around the shaft at said opening to prevent the entrance of foreign matter through the latter, the housing and the longitudinal members of the yoke having complementary bearing faces to permit relative longitudinal movements and relative rotary movements of limited extent about the longitudinal axis of the housing while preventing other relative movements, a cushion unit within the housing embraced by said yoke, stops in the housing at the ends of said cushion unit, and means to introduce a lubricant into the interior of the housing.

HERBERT E. VAN DORN.
